UNITED STATES PATENT OFFICE.

GERHARD OLLENDORFF, OF BERLIN-WILMERSDORF, AND AUGUST TANZEN, OF BERLIN-TREPTOW, GERMANY, ASSIGNEES TO ACTIEN GESELLSCHAFT FÜR ANILIN FABRIKATION, OF BERLIN, GERMANY.

COLOR PHOTOGRAPHY.

Application filed November 4, 1924. Serial No. 747,828.

To all whom it may concern:

Be it known that we, GERHARD OLLENDORFF and AUGUST TANZEN, citizens of the German Republic, residing at Berlin-Wilmersdorf, Germany, and Berlin-Treptow, Germany, have invented certain new and useful Improvements in Color Photography, of which the following is a specification.

This invention relates to the art of color photography.

In methods known as polychromatic screen plate processes, for producing color photographs a considerable portion of light incident on the plate or film is absorbed by the rulings, grains or the like in the screen plate and thus the effective sensitivity of the plate or film is diminished in proportion. This process is, therefore, not well suited for such short exposures as are necessary, from the stand point of optical considerations, for the photography of quickly moving objects.

For this reason, especially in the production of colored cinematographic pictures, it is practice to resort to the use of monochromatic pictures, such as are obtained by exposing highly sensitized panchromatic plates or films to the action of image-forming devices in conjunction with appropriate light filters of the primary colors, as is well understood, which pictures are then combined in well known manner to produce the composite color picture.

One method, according to which the three constituent color value positives are projected simultaneously, so as to be in exact optical superposition upon the screen, usually requires complicated apparatus.

Another method, according to which the color value positives are successively projected, necessitates a relatively high speed of the film which is thereby subjected to undue strains.

It is the object of the present invention to provide a method of producing composite colored pictures, which eliminates the above mentioned difficulties.

The method, briefly expressed, consists in photographing color valued positives upon a polychromatic screen plate.

In order to more fully explain the invention and the principles upon which it is based, reference is made to the accompanying drawings in which—

Fig. 1 represents a colored object to be photographed;

Figs. 2, 3 and 4 represent three color value positives made therefrom; and

Figs. 5, 6 and 7 the production of a composite color picture from the three color value positives shown in Figs. 2, 3 and 4.

The three color value positives *a*, *b* and *c* schematically represented in Figs. 2, 3 and 4 may be made in the usual manner and by any suitable apparatus well known in the art. For the sake of illustration it may be assumed that *a* represents a positive that has been printed from a negative which was produced by a camera and a red light filter. Similarly, positives *b* and *c* may be assumed to have been produced in identical manner from negatives made with green and blue filters, respectively.

The three color value positives are then photographed upon a polychromatic plate or film *P*, i. e. the pictures represented by appropriately illuminated color value positives as made in three color processes are superposed upon each other on the polychromatic screen, separately or simultaneously in any suitable manner.

This may be done, as indicated in Figs. 5, 6 and 7 by contact printing. The three color value positives *a*, *b* and *c* are successively brought into position upon a polychromatic plate or film *P* and illuminated by a suitable light source *L* in conjunction with the appropriate light filters *a*₁, *b*₁ and *c*₁, respectively.

While contact printing has been specifically referred to as one mode of producing the composite colored picture upon a polychromatic screen, any other modes whereby appropriately illuminated color value positives may be photographed in superposition upon a polychromatic screen come within the scope of the invention.

It is thus possible, by the present invention, to produce uniformly colored pictures of excellent color qualities which may be projected by simple projecting apparatus. Means for making accurate and pains-taking adjustments necessary for effecting exact superposition need be provided only once and any large number of colored films can be made thereby. Moreover, the accurate and tedious work necessary can be done at convenience and at ease.

We claim,—

1. The method of producing pictures which consists in making color value positives of an object and then photographing the color value positives, each illuminated by monochromatic light corresponding to it in superposition upon a polychromatic screen provided on its opposite side with a sensitive emulsion.
- 10 2. In the art of color photography, the step which consists in photographing color value positives, each illuminated by monochromatic light corresponding to it in superposition upon a polychromatic screen provided on its opposite side with a sensitive emulsion.
- 15 3. In the art of color photography, the steps which consist in making color value positives of an object and then superposing pictures of the object as represented by the different color value positives, each illuminated by monochromatic light corresponding to it upon a polychromatic screen provided on its opposite side with a sensitive emulsion.
- 25 4. In the art of color photography, the

step which consists in superposing pictures of an object as represented by different color value positives thereof, each illuminated by monochromatic light corresponding to it upon a polychromatic screen provided at its opposite side with a sensitive emulsion.

5. Method of producing color photographs, which consists in photographing the composite effects produced by color value positives, each illuminated by monochromatic light corresponding to it, upon a polychromatic screen provided on its opposite side with a sensitive emulsion.

6. Method of producing color photographs which consists in making color value positives of an object and then printing the color value positives in succession, each by monochromatic light corresponding to it, upon the same surface unit of a polychromatic screen provided on its opposite side with a sensitive emulsion.

In testimony whereof we affix our signatures.

GERHARD OLENDORFF.
AUGUST TANZEN.
